INTERCOMMUNICATING SYSTEM

Karl Ingemar Bertil Legerth, Goteborg, Sweden

Application December 19, 1946, Serial No. 717,276
In Sweden January 24, 1946

11 Claims. (Cl. 179—38)

1

The present invention relates to an intercommunicating system including a plurality of separate stations each comprising a combined transmitter and receiver, and at least two amplifiers.

One object of the invention is to provide a system in which any of the amplifiers may be used for the connection between two arbitrary stations.

Another object of the invention is to provide a system in which each station need not be connected with each amplifier by means of separate wires.

Other objects and advantages of the invention will be pointed out and evident to those skilled in the art from the following description taken in connection with the accompanying drawings, wherein there is shown, by way of illustration, a preferred embodiment of a system according to the invention.

In the drawings:

Figure 1 is a schematic diagram of a station.

Figure 2 is a schematic diagram of three relay groups belonging to a device for setting up a call.

Figure 3 is a more complete schematic diagram of a relay-group.

Figure 4 is a schematic diagram of a relay-unit adapted for selecting a relay-group not occupied by a call, and

Figure 5 shows a modified embodiment of a circuit shown in Fig. 3.

Referring to Fig. 1 the shown station is provided with a start key 1 and keys 5 for calling any of the other stations belonging to the system. Thus, the number of said keys 5 correspond to the number of stations in the system minus one. For the sake of simplicity only two keys 5 are shown here. Further, there is a restoring key 6 and a loud speaker 7 also usable as a microphone.

Each station is provided with six contacts, in the drawing designated *a*, *b*, *c*, *d*, *e*, and *cv*, for the connection of the station to the system and with two contacts, designated — and +, for the connection of the station to the plus and minus terminals of a source of current. Further, there are contacts *vII*, *vIII* etc. to a number corresponding to the number of the keys 5. From the manner of designating it is obvious that the station shown in Fig. 1 is called I and that the other stations are provided with a contact *vI*.

The contacts *a*, *b*, *c*, *d*, *e* in a station are permanently connected with corresponding contacts in a relay-set, one relay-set being provided for each station, which sets serve for switching-in

the corresponding station at a call. The contact *vII* is connected with the corresponding contact in all the other stations and further with a corresponding contact in said relay-sets. The contact *vIII* and corresponding contacts in the other stations are connected in the same way. Finally, the contact *cv* is permanently connected with the corresponding contact in the other stations and with a corresponding contact in a relay-unit for selecting an amplifier.

The diagram in Fig. 3 shows a relay-group comprising in the present case three relay-sets, each set having three relays 8, 9, 12. The relays 9 are impulse relays and have the purpose of preventing circle currents from arising. Impulse relays of the same kind as the relays 9 are preferably also provided for the switching-in of the relays 12 in the same manner as is shown for the relays 8 in the upper part of Fig. 3 and also in Fig. 2. According to Fig. 3 the loud speaker 7, for instance in station I, may be connected to an amplifier, not shown in the drawing, by means of the contacts *a* and *b* which through the make contacts 12*d* and 12*e* of the relay 12 are connected with a wire 26 which through a speaking or listening key 14 connects the loud speaker to the input or output of the amplifier (the wires 24 and 25). This connection is effected in the manner described as follows when the start key 1 in the calling station I is operated:

The contacts *a* and *b* in the relay-set of the station I can be connected with the speaking or listening key 14 or the amplifier through the wire 27, when the relay 8 is operated, and through the make contacts 8*b* and 8*c* of the relay 8. This is effected in the manner described as follows when the calling key 5 in any of the stations II and III and corresponding to the contact *vI* is operated.

In order to render several calls possible at the same time several relay-groups of the kind shown in Fig. 3 are provided. In Fig. 2 the principal arrangement of three relay-groups A, B and C of this kind is shown. As will be seen, the contact *vI* is connected with the relay 8 in the left relay-set in the figure in each group A, B, and C and in the same manner the contacts *vII* and *vIII* are connected to all three relay-groups. Analogously the contacts *a*, *b*, *c*, *d*, *e* of the station I are connected to the other contacts belonging to a relay-set in the left relay-sets in the figure in all groups, the contacts of the station II to the central relay-sets etc. though these contacts are not shown in Fig. 2 for clarity's sake.

In Fig. 4 there is shown a diagram of a relay-unit by means of which a disengaged relay-group A, B or C is selected. There is a separate relay arrangement having relays 15 and 16 for each group A, B and C and each relay arrangement is provided with contacts 17 and 18 which are connected with corresponding contacts in the relay-groups. Further, the station contact *cv* is connected to the relay-unit.

When the start key is operated the contacts *cv* connected with each other will be positive for a short period and a circuit will be closed through the contact 19 and the operating winding (the lower winding in the figure) of the relay 16A which will be operated and is held by its holding winding (the upper winding), one terminal of said last winding being connected with the contact 17A through the one make contact of the relay. It is assumed that said contact 17A is positive. By means of the other make contact of the relay 16 a circuit will be closed through the winding of the relay 15A with the result of the latter being operated. When the relay 15A is operated the contact 19 is opened and the contacts *cv* are instead connected with one terminal of the operating winding of the relay 16B through a cut-off contact of the relay 15B. Thus, when the next short positive impulse passes the contacts *cv* the relays 15B and 16B will be operated in substantially the same way as the relays 15A and 16A, as is described above, and the contacts *cv* will be connected with the operating winding 16C through the closed relay contacts 28 (of 15B) and 29 (of 15A) and the relay contact of the relay 15C.

When the start key 1 in Fig. 1 is operated the contact *e* will be connected with the negative terminal of the source of current through the contact 1c and a cut-off contact of a cut-off relay 2. This relay, however, is controlled by a control relay 3, the one terminal of the winding of said latter relay being permanently connected to the negative terminal of the source of current while the other terminal of said winding is connected with the plus terminal through the contacts 1d and 1b, when the start key is operated. Thus, the relay 3 is operated and its contact 3a closes a circuit through the relay 2 which will cut-off the connection of the contact *e* with the negative terminal of the source of current. Therefore, the contact *e* will be negative only for a short period.

When the start key is operated the contact *cv* (that is all contacts *cv*) will be positive for a short period through the contact 1b and a cut-off contact of the relay 2 which is energized and cuts-off the connection between the contact *cv* and the plus terminal of the source of current after a very short interval.

From what is described hereinbefore it is clear that the contact *e* becomes negative and the contact *cv* positive for a short period, when the start key is operated. As is seen from Fig. 4 the contact *cv* is connected with the contact 18A until the cut-off contact 19 is opened, which happens just when the contact *cv* becomes positive for a short period. At the next positive impulse through the contact *cv* the contact 18B will be positive for a short period and after a further impulse the contact 18C becomes positive.

According to Fig. 3 the contact 18 is connected through the wire 20 to one terminal of the operating windings of the relays 12, the other terminals of said windings being connected to the contacts *e*. As mentioned hereinbefore, this con-

nection in fact is effected through impulse relays (not shown) of the same kind as the relays 9 for the connection of the relays 8 to the wire 10. Assuming that the relay-unit according to Fig. 4 is in the position as shown and the start key in the station I is operated the relay 12 of the relay-group A and corresponding to the station I will be operated due to the short negative and positive impulses through the contacts *cv* and 18A, respectively. The relay is then held by a holding winding one end of which is connected to the negative terminal of the source of current while the other terminal of the winding is connected to the positive terminal of the source of current through the make-contact 12a and a cut-off contact of a restoring relay 13. From Fig. 3 it will also be seen that the contact 17 is connected to the positive terminal through the same cut-off contact.

By the operation of the relay 12 the loud speaker 7 of the station I has been connected to the input of the amplifier in the relay-group A as described hereinbefore. Simultaneously the station contact *d* has been connected to the wire 10 through the contact 12b, one end of the windings of the relays 9 being connected with one terminal of said wire. The other end of said windings is connected to the negative terminal of the source of current through a wire 22.

If then the calling key 5 in Fig. 1 corresponding to the contact *vII* is operated, one of the closed contacts (the upper in the figure) will connect one terminal of the winding of a calling relay 4 with the positive terminal of the source of current through a wire which comprises a condenser 24 of suitable capacity. The other terminal of the winding of the relay 4 is permanently connected to the negative terminal of the source of current. During the charging of the condenser 24 the winding will be passed by a current so that the relay 4 is energized during a short interval. Thus, the relay contacts 4a and 4b are closed with the result that the contacts *vII* and *d* are connected with the negative terminal of the source of current for a short period.

Returning to Fig. 3 it is found that the short positive impulse to the contact *d* causes that all relays 9 are energized for a short period. Thus, the contacts 11 of the relays 9 are closed so that one terminal of the operating windings of the relays 8 is connected with the negative terminal of the source of current through the wire 22 for a short period. The other terminals of said windings, however, are connected to the contacts *vI*, *vII* and *vIII* through wires 23. Of said contacts only the contact *vII* is temporarily connected to the positive terminal of the source of current with the result that only the relay 8 corresponding to the station II is operated and is held by means of a holding winding 8'. By the operation of the relay 8 the loud speaker 7 of the station II has been connected to the output of the amplifier belonging to the relay-group A and the stations I and II have been connected with each other.

From what is described hereinbefore it is clear that when a further station in the system is calling, a connection will be set up through the relay-group B, and when yet a further station is calling a connection will be set up through the relay-group C. If any of these groups then becomes disengaged it can immediately be used for a new call from any station in the system.

In order to reverse the direction of speaking it is necessary to switch the speaking or listening key 14. Impulses for this purpose are supplied

to the key 14 through a wire 21 connected to the contact c in the station I through a relay contact 12c. When the start key 1 of the calling station is again operated, the wire 21 is connected to the positive terminal of the source of current and the key 14 is switched in a manner not shown but known per se.

When the call is finished the restoring key 6 of the calling station is operated with the result that the contact 30 is closed, which contact is included, in a manner not shown here, in the circuit to the restoring relay 13 (Fig. 3). Said relay is now energized and the connection of the relays belonging to the relay-group A in question with the positive terminal of the source of current is cut-off. The relays are set in their normal positions and as also the connection of the contact 17 with the positive terminal of the source of current is cut-off the relays 15A and 16A (Fig. 4) are as well de-energized. When the key 6 is operated also the connection between the positive terminal of the source of current and the one terminal of the winding of the control relay 3 is cut-off, which relay up to that time has been held by a circuit through its make contact 3b. Therefore, this relay is as well de-energized.

As a summing up of the above it can be said that in a relay-group the relays 12 serve for the connection of a calling station to the amplifier of the group, the relays 8 connect the called station to the calling station in analogy with the setting up of a call in an exchange operated by hand, while the relays 9 give impulse for assigning in advance the setting up of a connection to an arbitrary station. Relays of the same kind as the relays 9 are preferably used, as mentioned above, for assigning in advance the setting up of a connection to a disengaged amplifier. According to Figs. 2 and 3 there is in each relay-group, A, B and C an impulse relay for each station. However, in Fig. 5 it is shown how in a relay-group there is only one impulse relay 9 having a number of make contacts 11 corresponding to the number of relays 8. One terminal of the windings of the relays 8 is connected with the negative terminal of the source of current through said make contacts 11 for a short period.

It is clear from the principle of the system that the number of possible calls is solely determined by the number of amplifiers included in the system and that said amplifiers may be used for calls from all stations of the system. If necessary, it is relatively easy to add one or more further relay-groups having an amplifier to an already existing system without it being necessary to draw any new wires to the stations. The new relay-group is only connected in parallel with the relay-groups already existing.

The contacts may be arranged in another way, for instance some of them belonging to the start key 1 may be transferred to the relay 2. The system may be supplied by a single source of current, but it is also possible to use a separate source of current for each relay-group and a separate source of current for the relay-unit. If balanced two-way amplifiers are used the speaking or listening keys may of course be omitted.

While the invention has been described with reference to a particular system for purposes of illustration, it will be understood that various changes may be made within the scope of the following claims.

I claim:

1. In an intercommunicating system, at least three separate stations each comprising a com-

bined transmitter and receiver, a number of amplifiers less than the number of stations, but at least two, a group of relays for each of said amplifiers, each of said groups comprising relay-sets individually connected with one of said stations, a relay-unit connected with said relay-groups and with said stations and adapted for selecting a relay-group not occupied by a call, a start key in each station for operating said relay-unit to select an idle relay-group and for operating said selected relay-group to connect the combined transmitter and receiver of a calling station to the amplifier belonging to said relay-group, and keys in each station for calling any of the other stations, said keys actuating the relay-group selected by said relay-unit to connect the transmitter and receiver of a called station to the amplifier belonging to said relay-group.

2. In an intercommunicating system, a plurality of separate stations each comprising a combined transmitter and receiver, a source of current, at least two amplifiers, a group of relays for each of said amplifiers, each of said groups comprising relay-sets individually connected with one of said stations, a relay-unit connected with said relay-groups and with said stations and adapted for selecting a relay-group not occupied by a call, a connecting relay in each of said relay-sets the operating winding of which having one terminal connected to a contact in the respective station and the other terminal connected to a contact in said relay-unit, which contact is common to all of said connecting relays in each relay-group, a start key in each station for operating said relay-unit to select an idle relay-group and to connect its contact common to all of said connecting relays in said selected relay-group to one terminal of said source of current and for connecting said contact in a calling station, which contact is connected to the winding of said connecting relays, to the other terminal of said source of current, the connecting relay of said selected relay-group belonging to the relay-set connected with said calling station thereby being actuated so that it connects the combined transmitter and receiver of said calling station to the amplifier belonging to said selected relay-group, and keys in each station for calling any of the other stations, said keys actuating the relay-group selected by said relay-unit to connect the transmitter and receiver of a called station to the amplifier belonging to said relay-group.

3. In an intercommunicating system, a plurality of separate stations each comprising a combined transmitter and receiver, a source of current, at least two amplifiers, a group of relays for each of said amplifiers, each of said groups comprising relay-sets individually connected with one of said stations, a relay-unit connected with said relay-groups and with said stations and adapted for selecting a relay-group not occupied by a call, a connecting relay in each of said relay-sets the operating winding of which having one terminal connected to a contact in the respective station and the other terminal connected to a contact in said relay-unit, which contact is common to all of said connecting relays in each relay-group, a start contact in each station connected with said relay-unit, a start key in each station for connecting said start contact in a calling station to one terminal of said source of current and for actuating said relay-unit to connect said start contact to said contact com-

mon to all said connecting relays in an idle relay-group and also for connecting said contact in a calling station, which contact is connected to the winding of said connecting relays, to the other terminal of said source of current, the connecting relay of said selected relay-group belonging to the relay-set connected with said calling station thereby being actuated so that it connects the combined transmitter and receiver of said calling station to the amplifier belonging to said selected relay-group, and keys in each station for calling any of the other stations, said keys actuating the relay-group selected by said relay-unit to connect the transmitter and receiver of a called station to the amplifier belonging to said selected relay-group.

4. In an intercommunicating system, a plurality of separate stations each comprising a combined transmitter and receiver, a source of current, at least two amplifiers, a group of relays for each of said amplifiers, each of said groups comprising relay-sets individually connected with one of said stations, a relay-unit connected with said relay-groups and with said stations and adapted for selecting a relay-group not occupied by a call, a connecting relay in each of said relay-sets the operating winding of which having one terminal connected to a contact in the respective station and the other terminal connected to a contact in said relay-unit, which contact is common to all of said connecting relays in each relay-group, a holding winding on said connecting relays, a start contact in each station connected with said relay-unit, a cut-off relay and a control relay in each station, a start key in each station for connecting said start contact in a calling station via a cut-off contact of said cut-off relay to one terminal of said source of current and for actuating said relay-unit to connect said start contact to said contact common to all said connecting relays in an idle relay-group and for connecting said contact in said calling station which contact is connected to the winding of said connecting relays, via another cut-off contact of said cut-off relay to the other terminal of said source of current and for energizing said control relay to energize said cut-off relay which again cuts off the connection between on the one hand said start contact and said contact connected to the winding of said connecting relays and on the other hand said source of current, the actuation of the start key in a calling station thereby causing transmission of a short impulse only to the operating winding of the connecting relay in said selected relay-group, the said relay then being held by its holding winding, the actuation of said connecting relay causing the connection of the combined transmitter and receiver of said calling station to the amplifier belonging to said selected relay-group, and keys in each station for calling any of the other stations, said keys actuating the relay-group selected by said relay-unit to connect the transmitter and receiver of a called station to the amplifier belonging to said relay-group.

5. In an intercommunicating system, a plurality of separate stations each comprising a combined transmitter and receiver, a source of current, at least two amplifiers, a group of relays for each of said amplifiers, each of said groups comprising relay-sets individually connected with one of said stations, a relay-unit connected with said relay-groups and with said stations and adapted for selecting a relay-group

75 not occupied by a call, a connecting relay in each of said relay-sets the operating winding of which having one terminal connected to a contact in the respective station and the other terminal connected to a contact in said relay-unit, which contact is common to all of said connecting relays in each relay-group a start contact in each station connected with said relay-unit, said start contacts in all stations being mutually connected, a start key in each station for connecting said start contact in a calling station to one terminal of said source of current and for actuating said relay-unit to connect said start contact to said contact common to all said connecting relays in an idle relay-group and also for connecting said contact in a calling station, which contact is connected to the winding of said connecting relays, to the other terminal of said source of current, the connecting relay of said selected relay-group belonging to the relay-set connected with said calling station thereby being actuated so that it connects the combined transmitter and receiver of said calling station to the amplifier belonging to said selected relay-group, and keys in each station for calling any of the other stations, said keys actuating the relay-group selected by said relay-unit to connect the transmitter and receiver of a called station to the amplifier belonging to said relay-group.

6. In an intercommunicating system, a plurality of separate stations each comprising a combined transmitter and receiver, a source of current, at least two amplifiers, a group of relays for each of said amplifiers, each of said groups comprising relay-sets individually connected with one of said stations, and a release relay, a relay-unit comprising a number of relay-sets equal to the number of relay-groups, each last-mentioned relay-set comprising two relays, one controlling the energization of the other and

70 connected with a group contact connected with a corresponding relay-group, and one terminal of the source of current and provided with a holding winding, a start key in each station for energization of said control relays which then are held by its holding windings which after said energization are connected between one terminal of said source of current and another group contact connected with said corresponding relay-group, the last mentioned group contact being connected with the other terminal of said source of current via a contact of the release relay of said group, the other relays of said relay-sets in the relay-unit then selecting an idle relay group and energizing the latter to connect the combined transmitter and receiver of a calling station to the amplifier belonging to said relay-group, and keys in each station for calling any of the other stations, said keys actuating the relay-group selected by said relay-unit to connect the transmitter and receiver of a called station to the amplifier belonging to said relay-group.

7. In an intercommunicating system, a plurality of separate stations each comprising a combined transmitter and receiver, a source of current, at least two amplifiers, a group of relays for each of said amplifiers, each of said groups comprising relay-sets individually connected with one of said stations, and a release relay, a relay-unit comprising a number of relay-sets equal to the number of relay-groups, each last-mentioned relay-set comprising two relays, one controlling the energization of the other and

being provided with an operating winding connected between a group contact connected with a corresponding relay-group, and one terminal of the source of current and provided with a holding winding, a start key in each station for energization of said control relays which then are held by its holding windings which after said energization are connected between one terminal of said source of current and another group contact connected with said corresponding relay-group, the last mentioned group contact being connected with the other terminal of said source of current via a contact of the release relay of said group, the other relays of said relay-sets in the relay-unit comprising a normal contact for connecting the first mentioned group contact via a calling station to one terminal of said source of power, which other relays in all said relay sets except one comprise also a make contact, said make contacts being connected in series with each other and with the normal contact of the relay which is without a make contact, said normal and make contacts selecting an idle relay group which is energized to connect the combined transmitter and receiver of a calling station to the amplifier belonging to said relay-group and keys in each station for calling any of the other stations, said keys actuating the relay-group selected by said relay-unit to connect the transmitter and receiver of a called station to the amplifier belonging to said relay-group.

8. In an intercommunication system a plurality of separate stations each comprising a combined transmitter and receiver, a source of current, at least three amplifiers a group of relays for each of said amplifiers, each of said groups comprising relay-sets individually connected with one of said stations, and a release relay, a relay-unit comprising a number of relay-sets equal to the number of relay-groups, each last-mentioned relay-set comprising two relays, one controlling the energization of the other and being provided with an operating winding connected between a group contact connected with a corresponding relay-group, and one terminal of the source of current and provided with a holding winding a start key in each station for energization of said control relays which then are held by its holding windings which after said energization are connected between one terminal of said source of current and another group contact connected with said corresponding relay-group, the last mentioned group contact being connected with the other terminal of said source of current via a contact of the release relay of said group, the other relays of said relay-sets in the relay-unit comprising a normal contact for connecting the first mentioned group contact via a calling station to one terminal of said source of power, which other relays in all said relay sets except one comprise also a make contact and in all said relay sets except two comprise a further make contact, said first mentioned make contacts being connected in series with each other and with the normal contact of the relay which is without a make contact, and said second mentioned make contacts being connected in series with each other and with the normal contact of the relay having a normal contact and only one make contact, said normal and make contacts selecting an idle relay group which is energized to connect the combined transmitter and receiver of a calling station to the amplifier belonging to said relay-group, and keys in each station for

calling any of the other stations, said keys actuating the relay-group selected by said relay-unit to connect the transmitter and receiver of a called station to the amplifier belonging to said relay-group.

5 9. In an intercommunicating system, a plurality of separate stations each comprising a combined transmitter and receiver, at least two amplifiers, a group of relays for each of said amplifiers, each of said groups comprising relay-sets individually connected with one of said stations, each set being provided with a connecting relay having an operating and a holding winding, a relay-unit connected with said relay-groups and with said stations and adapted for selecting a relay-group not occupied by a call, a start key in each station for operating said relay-unit to select an idle relay-group and for operating said selected relay-group to connect the combined transmitter and receiver of a calling station to the amplifier belonging to said relay-group and keys in each station for calling any of the other stations, said keys actuating said connecting relay in the relay-set corresponding to a called station in said selected relay-group to connect the transmitter and receiver of said called station to the amplifier belonging to said selected relay-group.

10 10. In an intercommunicating system, a plurality of separate stations each comprising a combined transmitter and receiver, a source of current, at least two amplifiers, a group of relays for each of said amplifiers, each of said groups comprising relay-sets individually connected with one of said stations, each set being provided with a connecting relay having an operating and a holding winding and with an impulse relay controlling the energization of said connecting relay, the windings of said impulse relays being 15 all connected in parallel to one terminal of said source of current, a relay-unit connected with said relay-groups and with said stations and adapted for selecting a relay-group not occupied by a call, a start key in each station for operating said relay-unit to select an idle relay-group and for operating said selected relay-group to connect the combined transmitter and receiver of a calling station to the amplifier belonging to said relay-group and keys in each station for calling any of the other stations, said keys actuating said impulse relays which connect one end of the operating windings of said connecting relays in said selected relay-group to one terminal of said source of current, the connecting relay in which the other end of its operating winding by means of the key corresponding to a called station is connected to the other terminal of said source of current being energized, which energized connecting relay thereby connects the 20 transmitter and receiver of said called station to the amplifier belonging to said selected relay-group.

11. In an intercommunicating system, a plurality of separate stations each comprising a combined transmitter and receiver, a source of current, at least two amplifiers, a group of relays for each of said amplifiers, each of said groups comprising relay-sets individually connected with one of said stations, each set being provided 25 with a connecting relay having an operating and a holding winding and with an impulse relay controlling the energization of said connecting relay, the windings of said impulse relays being all connected in parallel to one terminal of said source of current, a relay-unit connected with said re-

11

lay-groups and with said stations and adapted for selecting a relay-group not occupied by a call, a start key in each station for operating said relay-unit to select an idle relay-group and for operating said selected relay-group to connect the combined transmitter and receiver of a calling station to the amplifier belonging to said relay-group, a calling relay in each station, in which one end of the winding is connected to one terminal of said source of current and the other end via an open contact connected with the other terminal of said source of current, said latter connection comprising a condenser limiting the time of current flow in said connection to the period of charging said condenser, and keys in each station for calling any of the other stations, said keys actuating said impulse relays which connect one end of the operating windings of said connecting relays in said selected relay-group to one terminal of said source of current and said keys closing said open contact so that the connecting relay which corresponds to the

12

key belonging to a called station is energized, which energized connecting relay thereby connects the transmitter and receiver of said called station to the amplifier belonging to said selected relay group.
